UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

SPARKING DEVICE FOR INTERNAL-COMBUSTION ENGINES.

1,105,659.

Specification of Letters Patent.

Patented Aug. 4, 1914.

Application filed July 29, 1910. Serial No. 574,420.

To all whom it may concern:

Be it known that I, GOTTLÖB HONOLD, engineer, a subject of the German Emperor, residing at 11-13 Holzlaustrasse, Stuttgart, Germany, have invented certain new and useful Improvements in Sparking Devices for Internal-Combustion Engines; and I do hereby declare the following to be a full, clear, and exact description of the invention, such as will enable others skilled in the art to which it appertains to make and use the same.

My invention relates to sparking devices for internal combustion engines, and particularly to what are known in the art as sparking-plugs, that is to say, devices embodying a plug proper adapted to be screwed or otherwise inserted into the wall of the engine-cylinder and carrying fixed and movable sparking terminals, and an electro-magnet coil provided with a suitable core and pole-piece for which the movable sparking terminal serves as an armature.

The object of the invention, in addition to realizing a simple and economical construction, is to permit of the ready removal of the armature terminal from the plug, for purposes of substitution or repair, without the necessity of removing the plug proper from the cylinder, and, in some instances, without the necessity of removing or displacing the electromagnet coil. The construction and arrangement of the parts is likewise such that not only is a good conducting connection maintained between the magnet coil winding and the armature terminal, but also that the interior of the coil is securely sealed against the penetration of the gaseous products of combustion from the cylinder.

The characteristic features of my invention are illustrated, in a number of different forms or exemplifications, in the accompanying drawings, all of which illustrate the movable armature terminal as guided to move longitudinally or axially by the attraction of the electro-magnet coil, as against tension of a spring, which spring normally tends to hold the movable terminal in good conducting contact with the fixed terminal.

In the drawings,

Figure 1 represents, in longitudinal section, a sparking device embodying my invention, and wherein the pole piece governing the armature is shown as integral with the electro-magnet core. Figs. 2 and 3 rep-

resent like views of other forms or modifications of my invention, differing slightly in detail from each other, wherein the pole piece is shown as separate from the core, and wherein the spring connects the pole piece and armature terminal to form a composite entity. Figs. 3, 4 and 5 represent like views of other forms or exemplifications of my invention, wherein the pole piece and armature terminal may be removed without disassembling the magnet coil from the plug proper and without disturbing either of the latter. Fig. 6 represents, partly in elevation and partly in section, the spring connected removable pole piece and armature terminal, disassembled from the remaining parts of the device.

Similar letters of reference indicate similar parts throughout the several views.

The plug proper *a* is adapted to be inserted in the cylinder wall of the engine in any usual or preferred way, as, for instance, by screwing it into place, for which purpose it may be provided with a screw threaded shank, as shown. It carries the fixed terminal *c*, and the axially movable terminal *e*, the latter being contained within a guide tube *d*, which is insulated from the plug *a* by means of the porcelain or steatite insert *f*.

The sleeve *d* may serve as a convenient means for carrying the electro-magnet coil *b*, which may be screwed thereon, as shown, so as to be removable in disassembling the parts. In the construction shown in Figs. 1, 4 and 5, the pole piece of the core *h* is formed integral therewith, whereas, in the construction shown in the remaining figures, the pole piece is shown as an individual element *g* separate from the main body portion of the core. The upper end of the axially movable armature terminal *e* carries a spring *i*. This spring may engage a groove *c'*, as shown in Figs. 1, 2, 4, 5 and 6, or it may be screwed upon a screw-threaded projection of the armature terminal *e*, as shown in Fig. 3; and, in either case, it may be further secured in place upon the armature terminal *e* by soldering.

In the form shown in Fig. 1, the upper portion of the spring *i* enters a recess formed around the integral pole piece *g'*, and, in the construction shown in the remaining figures, the upper portion of the spring *i* surrounds the lower portion of the separate pole piece *g* and may, if so desired, be soldered thereto.

In Fig. 3, both the upper portion of the armature terminal *c* and the lower portion of the separate pole piece *g* are shown as screw-threaded, this construction permitting the spring to engage the screw-threads, and this connection may be made the more secure, if desired, by soldering the corresponding convolutions of the spring to the screw-threads with which they engage.

- 10 In order to prevent undue friction, when the armature terminal *c* slides in the sleeve *d*, a ring *k* of some hard material, such as steel, is inserted in the lower end of the sleeve *d*, the internal diameter of the ring 15 being somewhat smaller than that of the sleeve, so that, when forced into place, it will securely maintain its position. The upper end of the armature terminal *c* is carried by the spiral spring *i*. This method 20 of guiding the armature terminal *c* is of especial advantage when the sparking plug is arranged horizontally in the cylinder of the engine.

In order to maintain a good contact between the armature terminal *c* and the fixed terminal *e* and to regulate the stroke of the armature terminal *c*, notwithstanding the continuous wear caused by the action of the sparks and the corrosion due to the 25 products of combustion, annular disks *l* (see Fig. 4) of metal or other suitable material may be interposed between the upper end of the sleeve *d* and the pole piece end of the core, so that, by removing these disks, 30 one by one, as the armature terminal *c* wears away, the magnet may be screwed farther down on the sleeve, to attain the desired end.

For the purpose of obtaining a tight seal 40 between the interior of the cylinder magnet coil *b* and the interior of the plug, so that the products of combustion from the cylinder may not enter the interior of the coil, a cylindrical projection *m* is provided for the pole piece, which projection enters the 45 guide sleeve *d*, whereupon the lower surface *n* of the pole piece presses firmly against the upper edge of the guide sleeve *d*, or against the intermediate disks *l*, as the case may be.

50 The sparking plug can be taken to pieces with ease for the purpose of exchanging worn parts for new ones, in the following manner: In the construction shown in Fig. 1 the fixed pole piece *g'* is integral with the 55 magnet core *h*, so that when the magnet coil is screwed off the sleeve *d*, the core with its pole piece remains in the magnet coil and the armature terminal *c* and spring *i* are exposed and can easily be removed from the 60 guide casing *d* without the necessity of removing the plug *a* from the cylinder.

In the construction shown in Figs. 2 and 3 the pole piece *g* is only mechanically attached, as, for example, by riveting, soldering or the like, to the spring *i* which is sim-

ilarly attached to the armature *c* (see Fig. 6); thus, mechanically, the pole piece is a part of the spring and armature, while magnetically it belongs to the magnet core *h*. After the magnet coil has been unscrewed 70 from the sleeve *d*, the pole piece *g*, spring *i* and armature *c* are accessible and can easily be removed.

In the constructions shown in Figs. 1, 2 and 3, when the magnet coil is screwed on 75 to the sleeve *d*, the pole piece is thereby pressed against the upper edge face of the sleeve, thus making a tight joint therewith.

The construction shown in Figs. 4 and 5, in which the pole piece *g*, the spring *i* and 80 the armature terminal *c* are connected as described with reference to Fig. 2, are mainly differentiated from that already described, in that it is not necessary to unscrew the magnet coil from the plug in order to remove the armature terminal. As shown in Fig. 4, the core *h* with its pole piece *g* and the armature *c* may be removed when the screw *o* has been unscrewed. In Fig. 5 the core *h* having the pole piece *g* 85 is itself screw-threaded at its upper end, and is screwed into the bobbin of the magnet coil *b*. In this case, also, the pole piece *g*, spring *i* and armature terminal *c* are shown as forming a composite entity. These 90 parts may, however, be separately inserted.

The sparking device operates as follows: One pole of the source of current is connected to the metallic body of the engine, and is therefore in electrical connection with the plug *a*; the other pole is connected with the magnet coil *b*. At a suitable instant, the current traverses the magnet coil, one end whereof is in electrical connection with the armature terminal *c*, which is insulated 100 from the plug *a*. As long as the electromagnet is without current, the armature terminal *c* is held by the spring *i* against the terminal *e* and the circuit is closed through the coil, armature terminal *c* and plug *a*. As soon as a current impulse is sent through the coil, the armature terminal *c* is attracted by the pole piece *g* against the action of the spring *i* and contact between *c* and *e* is broken, producing the ignition 110 spark.

Having thus described my invention, what I claim is:

1. In a sparking device for cylinders of internal combustion engines, an electromagnet coil, a plug insertible in the cylinder and spaced apart from the coil, a contact terminal carried by the plug, an axially movable armature terminal projecting within said coil and normally contacting with said contact terminal, a sleeve 120 loosely surrounding the armature terminal and holding a coil in fixed relation to the plug, and a guide ring of rounded cross-section forming a substantially frictionless 125

guide for the armature terminal; substantially as described.

2. In a sparking device for the cylinders of internal combustion engines, an axially-movable armature terminal, a pole-piece therefor, and a coiled spring connecting the armature terminal with the pole-piece, but normally holding them out of contact with each other, said spring engaging 10 threads formed upon the terminal and pole-

piece the engaging convolutions of the spring being soldered in place; substantially as described.

In testimony whereof I have affixed my signature, in presence of two witnesses.

GOTTLOB HONOLD.
